FIG. 1 is a top plan view of a heat sink showing my new
design;FIG. 2 is a right side elevational view thereof; the left
side elevational view being a mirror image of that
shown;FIG. 3 is a front elevational view thereof; the rear eleva-
tional view being a mirror thereof;

FIG. 4 is a bottom plan view thereof;

FIG. 5 is a top plan view of a heat sink showing my new
modified design;FIG. 6 is a right side elevational view thereof, the left
side elevation being a mirror image of that shown;FIG. 7 is a front elevational view thereof, the rear eleva-
tional view being a mirror image of that shown; and,

FIG. 8 is a bottom plan view thereof.
